SPINNING FRAME CONTROL

David Robert Neely, Ellijay, Ga.

Application August 26, 1947, Serial No. 770,661

7 Claims. (Cl. 57—79)

1

This invention relates to textile machinery and more particularly to control mechanism for spinning frames.

The commercial spinning of thread or yarn involves the use of frames containing a large number of spindles with bobbins mounted thereon to receive the thread.

Heretofore it has been customary for the spinner to watch the operation of the spinning frame and upon completion of the winding to stop the machine and lower the ring rail to starting position. This operation requires constant attention on the part of the spinner, and it very often happens that while attending to other duties the bobbins are over-wound and necessitate removal of a portion of the yarn which is lost. This results in a very material loss in profits since all of the bobbins on one machine would be over-wound which necessitates removal of a very appreciable amount of yarn.

An object of the invention is to provide a control for spinning frames in which the frame is stopped and the ring rail lowered to starting position upon completion of the winding operation.

Another object of the invention is to provide a control for spinning frames which is completely automatic in operation and incorporating safety means which may be utilized to shut the spinning frame down and lower the ring rail at any desired time.

A further object of the invention is to provide a control for spinning frames which is purely mechanical in operation and which may be applied to all standard spinning frames with substantially no alteration thereof.

It is a further object of the invention to provide a control for spinning frames which is composed of relatively few parts, which is relatively simple in operation, and which will reduce the manual labor necessary in operating spinning frames.

Further objects and advantages of the invention will be apparent from the following specification taken in conjunction with the accompanying drawings, wherein:

Fig. 1 is an isometric view with parts in phantom for greater clarity and showing the spinning frame control in condition to start operating;

Fig. 2, a view similar to Fig. 1 and showing the spinning frame control substantially at the mid-point of its operating cycle;

Fig. 3, a view similar to Fig. 1 and showing the spinning frame control at the completion of its operating cycle; and

Fig. 4, a sectional view of the clutch, winding

2

drum and clutch engaging spring used in the apparatus of this invention.

With continued reference to the drawings there is shown therein in phantom a portion of a spinning frame comprising a housing 10 which houses the driving pulleys and gears for operation of the frame.

Extending at right angles to the housing 10 are bottom rails 11 and ring rails 12, it being understood that only one side of the frame is shown in the drawing and that the parts shown are duplicated on the opposite side of the spinning frame.

There is also provided a control rod 13 extending longitudinally of the frame and throughout the length thereof, this control rod terminating within the housing 10 and having provided on the end thereof belt shifting means, not shown, which is constructed and arranged to shift the drive belt for the spinning frame from a tight to a loose pulley when it is desired to shut down the machine. The rod 13 is mounted for limited longitudinal sliding movement and is normally operated by handles, not shown, mounted on the frame in a position convenient to the operator.

There is also provided in the conventional spinning frame a cross shaft 14 extending laterally of the frame and mounted for rotation thereon. A pedal 15 is fixed to the end of shaft 14 and a rod 16 extends upwardly from the pedal 15 and has its upper end secured to the ring rail 12.

In the normal manual operation of a spinning frame bobbins 17 are mounted on rotatable bobbin spindles 18 and the ring rail 12 occupies a position adjacent the lower end of the bobbins as shown in Fig. 3. The thread or yarn is spun and as the spinning progresses is wound on bobbin 17 starting from the lower end thereof and winding on progressively toward the upper end. The ring rail 12 having openings 19 receiving each bobbin moves upward during the winding operation until such time as the bobbin is filled. At this time the ring rail occupies a position adjacent the upper end of the bobbin as shown in Fig. 1. At this point the operator must manually shut down the machine and depress the pedal 15 which by means of rod 16 will move the ring rail 12 to the initial starting position adjacent the lower end of the bobbins as shown in Fig. 3.

The filled bobbins are then removed from the spindles 18 and the empty bobbins placed thereon whereupon the operation described above is repeated.

In order to remove the necessity of carefully observing the winding operation so that the frame

may be stopped at precisely the proper moment, applicant has provided means whereby the frame will automatically be stopped upon completion of the winding operation and the ring rail will be moved to its lowered starting position.

The control apparatus for accomplishing this result comprises a winding drum 20 slidably and rotatably received on a shaft 21 which is in turn rotatably mounted on brackets 22 and 23 secured to the spinning frame. Winding drum 20 is formed at one end thereof with an enlargement 24 in the outer radial face of which is formed clutch teeth 25.

Fixed on shaft 21 is a gear 26, and adjacent thereto and fixed on shaft 21 is a collar 27. Collar 27 is provided with clutch teeth 28 which are complementary to clutch teeth 25 and which are adapted for cooperating engagement upon sliding movement of the winding drum 20 toward collar 27.

Coil compression spring 29 surrounds the shaft 21 between an enlarged end portion 30 of winding drum 20 and a collar 30', this spring normally urging the clutch teeth 25 and 28 into interlocking engagement. Meshing with gear 26 is a pinion gear 31 fixed to another gear 32. This pair of gears are rotatably mounted on a bracket 33 secured to the housing 10 by a bolt 34. Gear 32 meshes with gear 35 which is part of the normal drive mechanism within the housing 10.

Depending from bracket 23 is a bracket 36 upon which is pivotally mounted at 37 a latch bar 38 having a notch 39 in the inner end thereof. Notch 39 is adapted to engage the shouldered portion 30 of winding drum 20 and hold the winding drum in its retracted position, as shown in Fig. 1, with the clutch teeth 25 and 28 out of engagement. There is also provided a tension spring 40 which normally urges the notch 39 into engagement with the enlarged portion 30. Also pivotally mounted on bracket 36 at 41 is a clutch reset lever 42, the upper end of which is provided with a fork 43 adapted to engage the inner radial surface of enlarged portion 30 to move the winding drum and clutch teeth 20 toward the right as viewed in Fig. 1 when the lower end of the reset lever 42 is moved downwardly.

In order to operate the latch bar 38 and clutch reset lever 42 there is provided on cross shaft 14 a clutch control bar 44 fixed against relative rotation with respect thereto. Adjacent the opposite end of bar 44 there is pivotally mounted thereon at 45 a latch bar operating member 46, the upper end of which is slotted and slidably engages latch bar 38. The slotted end portions 47 of member 46 are held against movement longitudinally of latch bar 38 by pins 48 on each side of the slotted end portions 47. Also received between the slotted end portions 47 is a bolt 49 which may be clamped in any desired position to adjust the point at which the latch bar 38 will be operated. Also mounted on bar 44 adjacent the end thereof is a pin 50 which upon movement of bar 44 downwardly is adapted to engage the lower portion of clutch reset lever 42 to actuate the same.

In order to actuate the control rod 13 to shift the driving belt from a tight to a loose pulley, there is provided a cable 51 attached at one end to the winding drum 20 and leading through a pulley 52 mounted on bracket 53, the opposite end of the cable 51 being attached to a member 54 secured to rod 13 against relative movement therebetween by a setscrew or the like 55. It will thus be seen that upon rotation of the winding

drum 20 the cable 51 will be wound thereon, and as a result will pull rod 13 toward the left as viewed in Fig. 1 thus shifting the drive belt from one pulley to another.

In order to move the ring rail 12 from the upper position shown in Fig. 1 to the lower or starting position shown in Fig. 3, there is provided a second cable 56 attached at one end to the winding drum 20 and leading through a pulley 57 attached to a bracket 58 to a sector 59 fixed on the shaft 14 against rotation relative thereto. It will thus be seen that upon rotation of the winding drum the cable 56 will be wound thereon and will pull the sector 59 in a counter-clockwise direction, as shown in Fig. 1, thus rotating the shaft 14 and pulling ring rail 12 downwardly by means of rod 16.

To facilitate holding the ring rail in the down or inoperative position, there is provided a latch bar 60 pivotally mounted at 61 on a bracket 62 secured to the spinning frame. Latch bar 60 is provided with a latch member 63 and a foot engaging portion 64 by means of which latch bar 60 may be moved to unlatching position or toward the left as viewed in Fig. 1. Mounted on the cross shaft 14 against rotation relative thereto and adapted to engage latch member 63 is a bar 65 which may be clamped to shaft 14 in any suitable manner. Upon rotation of shaft 14 in a counter-clockwise direction as viewed in Fig. 1 the outer end 66 of member 65 will engage under the latch member 63 as shown in Fig. 3 to hold the ring rail 12 in lowered position.

It is sometimes desirable in the operation of spinning frames to stop the frame prior to completion of the spinning and winding operation and to return the ring rail to its lowered position. Consequently there has been provided means for initiating operation of applicant's control mechanism in order to stop the spinning frame and return the ring rail to lowered position at any desired time. This means may conveniently comprise a control handle 67 pivotally mounted as at 68 on a part of the frame convenient to the operator. One end of control handle 67 is pivotally connected at 69 to a rod 70 which may slidably extend through a guide sleeve 71 secured to the frame. The opposite end of rod 70 is pivotally attached at 72 to latch bar 38. It will thus be seen that by actuation of the control handle 67 rod 70 may be moved downwardly as shown in Fig. 1, thus releasing latch bar 38 and allowing winding drum 20 to start revolving which will stop the frame and lower the ring rail 12 to the starting position as shown in Fig. 3.

The operation of the device is as follows:

Starting with the ring rail 12 in its lowered position, as shown in Fig. 3, and with empty bobbins installed on the spindles 18, the operator moves latch bar 60 to the left by engaging portion 64 with his foot, thus releasing latch member 63 from member 66 and allowing the ring rail 12 to start moving upwardly. At the same time control rod 13 would be moved to the right to shift the drive belt from a loose pulley to a tight pulley. As the spinning and winding operation progresses, the ring rail 12 moves upwardly until it reaches the portion adjacent the upper ends of the bobbins 17 as shown in Fig. 1 at which time the mechanism comprising this invention begins to function.

As will be seen from an inspection of the drawings, upon movement of the ring rail 12 upwardly, bar 44 will move in a clockwise direction, as

viewed in Fig. 1, thus causing the slotted bar 46 to slide upwardly on latch bar 38 until bolt 49 which has been properly adjusted in the bar 46 engages and releases latch bar 38, allowing the winding drum and clutch teeth 25 to move to the left into engagement with teeth 28. At this point winding drum 20 driven by the clutch teeth 25 and 28 and the gearing associated therewith will commence to revolve, thus winding cables 51 and 56 thereon. This will result in sliding rod 13 to the left, thus shifting the belt from driving position to neutral position and at the same time will rotate shaft 14 in a counter-clockwise direction as viewed in Fig. 1 to lower the ring rail to starting position, as shown in Fig. 3. The operator will then remove the filled bobbins and replace them with empty bobbins and the process as described above will be repeated.

From a consideration of the above description, it will be seen that applicant has provided a relatively simple completely automatic and wholly mechanical control for spinning frames which will operate to stop the frame and lower the ring rail at the completion of the spinning and winding operation and which may be set in operation at any desired time during the spinning operation to stop the machine and lower the ring rail for any reason whatsoever. However, in its normal operation control thereof will be completely automatic as a result of the upward movement of ring rail 12 to a point where the bobbins are filled and ready to be removed. It will also be obvious that spinning frames equipped with a control of this type will require much less attention on the part of the operator and will result in a material saving due to occasional overwinding of the bobbins as a result of inattention on the part of the operator.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A control mechanism for spinning frames provided with a drive belt, tight and loose pulleys, a belt shifter rod, drive gears, a rotatably mounted cross shaft, bobbin spindles, a ring rail and means connecting said ring rail and said cross shaft for upward and downward movement of said ring rail upon rotation of said cross shaft, said control mechanism comprising a shaft rotatably mounted on said frame, gearing for rotating said shaft, a winding drum rotatably and slidably received on said shaft, clutch teeth on said winding drum, cooperating clutch teeth on a collar fixed to said shaft, spring means tending to urge said clutch teeth into driving engagement, a latch bar constructed and arranged to engage said winding drum and hold said clutch teeth out of engagement, a clutch reset lever constructed and arranged to engage said winding drum to move said clutch teeth out of engagement, a cable having one end attached to said winding drum and the other end attached to the belt shifter rod whereby upon rotation of said winding drum to wind said cable thereon said belt shifter rod will be moved to shift said drive belt from a tight to a loose pulley thus stopping the frame, a second cable having one end attached to said winding drum and the opposite end attached to a sector fixed on said cross shaft whereby upon rotation of said winding drum to

wind said second cable thereon said cross shaft will be rotated to move said ring rail downwardly, a clutch control bar fixed to said cross shaft, means on said clutch control bar engaging said latch bar to release the same upon movement of said clutch control bar with rotation of said cross shaft in one direction, said clutch control bar being further provided with means constructed and arranged to engage said clutch reset lever upon movement of said clutch control bar in the opposite direction whereby said clutch teeth are disengaged, and means fixed on said cross shaft constructed and arranged to cooperate with foot operated latch means pivotally mounted on said frame to hold said ring rail in lowered position.

2. A control mechanism for spinning frames provided with a drive belt, tight and loose pulleys, a belt shifter rod, drive gears, a rotatably mounted cross shaft, bobbin spindles, a ring rail and means connecting said ring rail and said cross shaft for upward and downward movement of said ring rail upon rotation of said cross shaft, said control mechanism comprising a shaft rotatably mounted on said frame, gearing for rotating said shaft, a winding drum freely rotatable on said shaft, clutch means constructed and arranged to drive said drum from said shaft, resilient means tending to urge said clutch means into driving engagement, a latch bar constructed and arranged to hold said clutch means in disengagement, a clutch reset lever constructed and arranged to disengage said clutch, a cable attached to said winding drum and to said belt shifter rod to move said rod upon rotation of said winding drum this shifting said drive belt from a tight to a loose pulley, a second cable attached to said winding drum and to a sector fixed on said cross shaft and operable to rotate said cross shaft upon rotation of said winding drum to move said ring rail downwardly, a clutch control bar fixed to said cross shaft, means on said bar to engage said latch bar to release the same upon rotation of said cross shaft in one direction, means on said clutch control bar to engage said clutch reset lever upon movement of said cross shaft in the opposite direction whereby said clutch is disengaged and means fixed on said cross shaft constructed and arranged to cooperate with latch means to hold said ring rail in lowered position.

3. A control mechanism for spinning frames provided with a drive means, a control for said drive means, a rotatably mounted cross shaft, bobbin spindles, a ring rail and means connecting said ring rail and said cross shaft for upward and downward movement of said ring rail upon rotation of said cross shaft, said control mechanism comprising a winding drum, a driving means for said winding drum, cooperating clutch teeth on said winding drum and said driving means, means normally urging said clutch teeth into driving engagement, a latch bar to hold said clutch teeth out of engagement, a clutch reset lever to move said clutch teeth out of engagement, a cable attached to said winding drum and to said drive control means whereby upon rotation of said winding drum said frame will be stopped, a second cable attached to said winding drum and to a sector fixed on said cross shaft whereby upon rotation of said winding drum, said cross shaft will be rotated to move said ring rail downwardly, a clutch control bar fixed to said cross shaft, said clutch control bar having means engaging said latch bar to release the same upon movement of said clutch control bar upon rota-

tion of said cross shaft in one direction, said clutch control bar being further provided with means constructed and arranged to engage said clutch reset lever upon movement of said clutch control bar in the opposite direction whereby said clutch teeth are disengaged and means to latch said ring rail in lowered position.

4. A control mechanism for spinning frames provided with a drive belt, tight and loose pulleys, a belt shifter rod, drive gears, a rotatably mounted cross shaft, bobbin spindles, a ring rail and means connecting said ring rail and said cross shaft for upward and downward movement of said ring rail upon rotation of said cross shaft, said control mechanism comprising a winding drum, means for rotating said winding drum, a clutch between said rotating means and said winding drum, resilient means normally urging said clutch into engagement, means to hold said clutch disengaged, means to disengage said clutch, means connecting said winding drum and said belt shifter rod whereby upon rotation of said winding drum said belt shifter rod will be moved to shift said drive belt from a tight to a loose pulley, means connecting said winding drum and a sector on said cross shaft whereby upon rotation of said winding drum said cross shaft will be rotated to move said ring rail downwardly, means on said cross shaft to release said clutch holding means upon rotation of said cross shaft in one direction, means to disengage said clutch upon rotation of said cross shaft in the opposite direction, and means on said cross shaft cooperating with means on said frame to latch said ring rail in lowered position.

5. For use with a spinning frame having drive control means, a rotatably mounted cross shaft adapted upon rotation thereof to raise or lower a ring rail, a control mechanism comprising a winding drum, means to rotate said winding drum, control means to said rotating means constructed and arranged to start or stop said winding drum, means connecting said winding drum with said drive control means, means connecting said winding drum to said cross shaft whereby upon rotation of said winding drum, said drive control means will be actuated to stop said frame

and said cross shaft will be rotated to lower said ring rail, means on said cross shaft constructed and arranged to actuate said rotating control means and means on said cross shaft cooperating with means on said frame to latch said ring rail in lowered position.

6. A control mechanism for spinning frames provided with a drive means, a control for said drive means, a rotatably mounted cross shaft, 10 bobbin spindles, a ring rail and means connecting said ring rail and said cross shaft for upward and downward movement of said ring rail upon rotation of said cross shaft, said control mechanism comprising actuating means for said drive control means and for said rotatably mounted cross shaft whereby upon operation thereof said drive control means will be operated to stop said frame and said cross shaft will be rotated to lower said ring rail, means on said cross shaft constructed and arranged to control the operation of said actuating means and means on said cross shaft cooperating with means on said frame to latch said ring rail in lowered position.

7. A control mechanism for spinning frames 25 provided with a drive means, a control for said drive means, a rotatably mounted cross shaft, bobbin spindles, a ring rail and means connecting said ring rail and said cross shaft for upward and downward movement of said ring rail upon rotation of said cross shaft, said control mechanism comprising actuating means for said drive control means and for said rotatably mounted cross shaft whereby upon operation thereof said drive control means will be operated to stop said frame and said cross shaft will be rotated to lower said ring rail and means on said cross shaft constructed and arranged to control the operation of said actuating means.
